UNITED STATES PATENT OFFICE.

EDWARD SCHUMANN AND ALBERT PREPEJCHAL, OF CHICAGO, ILLINOIS, ASSIGNEES TO
JOSEPH SALTZMAN, OF CHICAGO, ILLINOIS.

GARMENT-PRESSING MACHINE.

No. 927,081.

Specification of Letters Patent.

Patented July 6, 1909.

Application filed November 11, 1907. Serial No. 401,578.

To all whom it may concern:

Be it known that we, EDWARD SCHUMANN and ALBERT PREPEJCHAL, citizens of the United States, residing at Chicago, in the county of Cook and State of Illinois, have invented certain new and useful Improvements in Garment - Pressing Machines, of which the following is a specification, reference being had therein to the accompanying drawing.

Our invention relates to garment-pressing machines, and has primarily for its object the production of a machine for this purpose operated by fluid pressure, such as compressed air.

Other objects of our invention relate to certain specific features in this general type of machine as will be made plain in the following specification, and the invention consists of the arrangements and combinations of parts hereinafter more particularly described and then pointed out in the appended claims.

In the accompanying drawing, which illustrates a practical embodiment of our invention and in which like reference numerals refer to similar parts in the several figures, Figure 1 is a front view in elevation of a machine embodying our invention. Fig. 2 is an enlarged detail view partly in section showing a compressed air cylinder and associated parts, a valve casing and a valve mechanism, and connections employed to control and convey the supply of air to the cylinder, showing the valve in one position; and Fig. 3 is a detail sectional view of the valve mechanism showing the valve in its other position.

The reference numeral 4 designates the standards of a suitable table 5 or other support, upon the upper face of which and near each end thereof are secured standards or uprights 6 and 7, the former having wings 8 adapted to receive screws 9 of clamp 10, which may be of any preferred form and adapted to lock one end of the pressing-board 11 securely to the standard 6, the other end resting upon the standard 7.

A cylinder 12 vertically disposed below the table is closed at its lower end by a head 13 having a thickened portion of slightly less diameter than the cylinder bore and adapted to enter the same and provided with a peripheral flange 14 with which the

end of the cylinder contacts. The flange is laterally extended at a plurality of points to provide wings 15 adapted to receive rods 16 which are threaded at their lower ends to receive nuts 17 which bear against the wings. The upper end of the cylinder is closed by a flanged head 18 having suitable lateral extensions or wings 19 which are also adapted to receive the rods 16, it being understood that there are the same number of wings on each head. The rods 16 are threaded to receive the nuts 20 and 21 which when set bear upon the upper and lower surfaces of the wings 19 and thus lock the parts of the cylinder in position. The rods 16 extend upwardly through the table 5 and through a plate 22 thereon, and are threaded at their upper ends to receive nuts 23 which bear upon the plate and hold the parts securely in position upon the table.

The head 18 is provided with a suitable stuffing box 24 through which a piston-rod 25 passes, and which is provided with a suitable piston-head 26 within the cylinder. The rod 25 passes through the table and is guided in an upright tubular sleeve or guide 27 integral with the plate 22. The upper end of the rod is reduced as shown at 28 to loosely receive a collar 29, which is held thereon by a nut 30 and which carries an arm 31 upon which a pressing-iron 32 is pivotally mounted. The iron may of course be of any suitable type adapted to be heated in any suitable manner, the form shown being an ordinary gas-heated iron receiving its supply from any source through the connection 33.

A valve-casing 34 is secured in any preferred manner to the under side of the table as by means of the screws passing through a flange or suitable ears on the top 35 of the casing. As shown in the drawing the top is made integral with the valve-casing, the other end of which is closed by a cap 36 adapted to be threaded upon the lower end thereof. A valve-stem 37 passes downwardly through a suitable opening in the cap and is operatively connected by a draw-link 38 to a treadle 39 of any desired type which is suitably fulcrumed to a depending bracket 40 carried by a cross-brace 41 secured to the standards. The valve-stem carries on its inner portion and at a suitable distance apart a pair of valves 42 and 43, which are preferably in the nature of piston heads snugly

fitting the bore of the valve-casing and provided with suitable packing rings. It is also to be understood that the lower end of the valve-casing may be provided with a suitable 5 stuffing box. A suitable expansion spring 44 is carried on the valve-stem and its ends react against the cap 36 and the lower face of the valve 42 to hold the valves in their normal raised position as shown in Fig. 2.

- 10 It is clearly apparent that the valve-casing and inclosed valves provide substantially a chambered piston having two piston-heads suitably spaced apart, and that the piston thus formed may control connections between 15 the valve-casing and cylinder 12 by which the piston 26 may be quickly moved from one position to another by air or other fluid pressure being admitted and exhausted from the opposite ends of the cylinder 20 through the lead pipes or connections. For this purpose the valve-casing is connected to any suitable source of pressure-fluid supply, as, for instance, the compressed-air tank or the like 45, by a supply pipe 46 which enters the casing at a point just above the valve 42 when it is in its normal position, as shown in Fig. 2. A pipe 47 opening into the casing at a point just below the valve 43 leads to and enters the bottom of the cylinder 12 below the 30 piston head, and a pipe 48 leading from the valve-casing to the cylinder enters at one end into the former below the valve 42 and at its other end through the head 18 of the latter above the piston head, all as shown in Fig. 2. 35 It is of course to be understood that these pipes communicate with the valve-casing and cylinder through suitable openings and are secured therein in any preferred way to prevent leakage. The casing 34 is provided 40 near its top and bottom with exhaust ports 49 and 50, respectively.

In the operation of our device, which is primarily designed to be used when great pressure is required, as in pressing seams and 45 stitched edges, the valves are normally in the position shown in Fig. 2 being held by the action of the spring so that the valve 42 is below the point where the supply pipe 46 enters the valve-casing and the valve 43 50 above the opening of the pipe 47. In this position of the valves it is obvious that the compressed air entering the valve-casing through the supply pipe 46 passes into the pipe 47 and therethrough into the lower end 55 of the cylinder and impinging against the bottom of the piston-head moves it upward and with it the piston-rod to raise the iron from the pressing-board, in which position it is adapted to be swung to one side while 60 the material is adjusted upon the board, and it is obvious that it may be turned in any direction desired. When the material to be pressed has been placed upon the board the operator depresses the treadle which draws 65 the valve-stem downward against the action

of the spring 44 until the valve 43 is below the entrance of the pipe 47 to the valve-casing and the valve 42 is below the entrance of the pipe 48 therein, as clearly shown in Fig. 3. When the valves are moved to this 70 position the compressed air passes from the casing 34 out through the pipe 48 into the cylinder above the piston-head and impinging thereagainst moves it downward carrying the piston-rod with it to bring the pressing-iron into pressing engagement with the material. It is obvious that during this movement the air or other fluid-pressure medium in the cylinder below the piston-head will exhaust back through pipe 47 and exhaust-opening 49 which obviously are placed in communication when the head or valve 43 uncovers the former. When the operator releases the treadle the spring returns the valves to their normal position as shown in 80 Fig. 2; and the compressed air supply being thus shut off from pipe 48 and turned into pipe 47, the air in the cylinder above the piston-head will return through the pipe 48 into the valve-casing and exhaust through 90 the port 50, and the compressed air will enter the cylinder below the piston-head as before described. It is evident that as supply pipe 46 enters the valve-casing at a point intermediate the two valves they are always 95 balanced and in their normal position bring the pipe 47 into communication with the supply pipe 46 and establish communication between pipe 48 and exhaust 50, and in their depressed position place the pipe 48 into 100 communication with the pipe 46 and establish communication between pipe 47 and exhaust 49.

The specific form of the cylinder is of advantage as it enables the parts to be easily 105 and readily assembled and disassembled. For example, all the parts of the cylinder may be united by the rods 16 and their nuts into a unitary or complete device ready for mounting on the table which may be accomplished by merely passing the rod 25 up through its sleeve, placing the plate 22 over the upper ends of rods 16 and applying the nuts 23. Also, by merely removing the nuts 110 17 the cylinder may be detached for cleaning etc. without the inconvenience of disassembling other parts, it being apparent that the pipe 47 may be made flexible for this purpose and that the connection of the pipe 48 with the head 18 allows all the other parts 115 to remain undisturbed.

The sleeve 29 affords an extended bearing on the post 28, and is free to revolve thereon to move the iron into and out of action over the pressing-board.

By the construction shown the piston in the cylinder may be quickly moved in either direction, and when depressed it exerts a powerful and constant pressure on the pressing-iron.

While we have described our invention with relation to a structure in which it may be embodied, we do not limit ourselves to any such specific form, it being obvious that 5 the structure may be varied in different ways without departing from the scope of our invention.

We claim:

1. In a device of the class described, a 10 table, a pressing-board on the table, an iron, a cylinder on the underside of the table, a piston-rod having a head in the cylinder and supporting the iron above the board, a compressed-air tank, a casing separate from and 15 between the tank and cylinder, a pipe leading from the tank to said casing, pipes leading from said casing to said cylinder on each side of the head therein, and a valve in the casing to connect the first pipe to either of 20 the second pipes.

2. In a device of the class described, a 25 table, a pressing-board mounted thereon, an iron, a cylinder on the underside of the table, a piston in the cylinder, connections between the piston and the iron extending above the table to support the iron at the board, a compressed air tank, a casing supported on the underside of the table and separate from, and between the tank and 30 cylinder, a connection between the tank and casing, connections leading from the casing to opposite ends of the cylinder, and means below the table to place either of the latter connections independently of the other in 35 communication with the tank.

3. In a device of the class described, a 40 table, a pressing-board mounted thereon, an iron, a cylinder on the underside of the table, a piston in the cylinder, connections between the piston and the iron extending above the table to support the iron at the board, a compressed-air tank, a casing supported on the underside of the table and separate from and between the tank and 45 cylinder, a connection between the tank and casing, connections leading from the casing to opposite ends of the cylinder, and valves in the casing adapted to be moved to place either of the latter connections independently of the other in communication with the tank, and means below the table to move the valves.

4. In a device of the class described, a 50 table, a pressing-board mounted thereon, an iron, a cylinder on the underside of the table, a rod having a piston-head in the cylinder and extending above the table to support the iron at the board, a compressed-air tank, connections between the tank and cylinder to admit air above and below the head of the cylinder, a casing supported on the underside of the table and separate from the cylinder and with which the connections communicate, a valve in the casing control-

ling the connections, and a treadle to operate 65 the valve.

5. In a device of the class described, a 70 table, a pressing-board mounted thereon, a cylinder on the underside of the table, an iron, a rod having a piston-head in the cylinder and extending above the table to support the iron, a compressed - air tank, a valve-casing supported on the underside of the table and separate from the cylinder, a pipe leading from the tank to the casing, 75 pipes leading from the casing to the cylinder, and a valve-mechanism to alternately establish communication between one of the latter pipes and the former pipe.

6. In a device of the class described, a 80 table, a pressing-board mounted thereon, an iron, a cylinder mounted on the underside of the table, a piston in the cylinder, connections between the piston and the iron extending above the table to support the iron 85 at the board, a compressed-air tank, a casing mounted on the underside of the table, a connection between the tank and casing, connections leading from the casing to opposite ends of the cylinder, valves in the 90 casing normally positioned to place the tank in communication with the connection leading from the casing to one end of the cylinder to raise the piston, means to move the valves to place the tank in communication 95 with the other connection to depress the piston, means in the casing to restore the valves to normal position, and an exhaust port in the casing for each of the connections leading thereto from the cylinder.

7. In a device of the class described, a 100 pressing-board, an iron, a cylinder, a piston-rod carrying said iron and having a head in said cylinder, a compressed-air tank, a casing having upper and lower exhaust ports, a piston in said casing having upper and lower heads, a spring in said casing holding said piston with its upper head closing the upper exhaust, a connection from the tank to the casing intermediate the 105 heads, a connection from the upper end of the casing to the lower end of the cylinder and normally in extension of the tank-connection, a connection from the lower end of the casing to the upper end of the cylinder 110 and normally in extension of the lower exhaust, and a treadle to move the piston in the casing to close the upper cylinder-connection and open the lower cylinder-connection.

In testimony whereof we affix our signatures in presence of two witnesses.

EDWARD SCHUMANN.
ALBERT PREPEJCHAL.
